UNITED STATES PATENT OFFICE

JOHN WILLIAM COX, DECEASED, LATE OF NEWARK, NEW JERSEY, BY GEORGE A. S. COOPER, ADMINISTRATOR, OF NEWARK, NEW JERSEY, ASSIGNOR TO THE NESTLE-LEMUR COMPANY, OF NEW YORK, N. Y., A CORPORATION OF OHIO

DESIGN FOR A PLUG CONNECTER

Application filed January 6, 1932. Serial No. 42,384. Term of patent 7 years.

To all whom it may concern:

Be it known that JOHN WILLIAM Cox, late a citizen of the United States, and resident of Newark, in the county of Essex and State of New Jersey, deceased, invented a new, original, and ornamental Design for Plug Connecters, of which the following is a specification, reference being had to the accompanying drawings, forming part thereof.

In the drawings—

Figure 1 is a plan view of a plug connecter, showing the new design;

Figure 2 is an edge elevation thereof; and
Figure 3 is an end elevation thereof.

What is claimed is:

The ornamental design for a plug connecter, as shown.

GEORGE A. S. COOPER,
Administrator of the Estate of John William Cox, Deceased.
